By W. D. Kelly # UNITED STATES PATENT OFFICE.

JOHN A. SERRELL, OF BAYONNE, NEW JERSEY, ASSIGNOR TO WARREN WEBSTER AND COMPANY, A CORPORATION OF NEW JERSEY.

VALVE DEVICE FOR STEAM-HEATING SYSTEMS.

SPECIFICATION forming part of Letters Patent No. 700,569, dated May 20, 1902.

Application filed March 19, 1900. Serial No. 9,476. (No model.)

To all whom it may concern:

Be it known that I, JOHN A. SERRELL, of Bayonne, county of Hudson, and State of New Jersey, have invented an Improvement in 5 Valve Devices for Steam-Heating Systems, of which the following is a specification.

My invention relates to valve devices for steam-heating systems; and it consists of certain improvements, which are fully set forth 10 in the following specification and are shown in the accompanying drawings.

In a suction system of steam-heating, or one in which a partial vacuum or lower pressure is maintained in the returns or on the 15 outlet side of the valve for the purpose of withdrawing the air and water of condensation, it is customary to employ an automatically-controlled valve-piece to control the thoroughfare and the discharge of the water 20 of condensation, while preventing the escape of uncondensed steam. It frequently results that owing to a sudden or excessive condensation in a radiator or drying cylinder there is a lower pressure created therein than 25 exists in the return, and as the automatic valves under these conditions are open it results that the water of condensation is drawn back through the open valves into the radiator or heater. It is the object of my invention 30 to overcome this difficulty by providing the valve device with an auxiliary check-valve in addition to the automatically-controlled valve-piece, which also controls the thoroughfare, but is so arranged as to be 35 normally held open by the suction or lower pressure in the return and to close automatically when the pressure on the inlet side of the valve-body or in the radiator is reduced below the pressure on the outlet side or in 40 the return. In carrying out this part of my invention I so arrange the check-valve that it will be opened by the suction or lower pressure in the discharge side, but will remain closed automatically when the pressures are 45 equal or the suction is relieved or its direction is reversed.

In the drawings, Figure 1 is a vertical sectional view of a valve device embodying my invention. Fig. 2 is a perspective view, in-

verted, of the check-valve. Fig. 3 is a plan view of the valve seat-piece shown in Fig. 1.

A is the valve-body, having the inlet a and the outlet b and the thoroughfare c, which is positively controlled by the main automatic valve-piece B.

C is the independent check-valve, which independently controls the thoroughfare c. The main valve-piece is operated automatically. In the construction shown it is a thermostatic expanding piece; but the invention may be 60 employed with other forms of automatic valve-pieces.

The check-valve C is so arranged that the suction or lower pressure on the outlet side of the valve will open it and the relief of the 65 suction or the reversal of its direction will cause it to close. In the construction shown the check-valve consists of a plate adapted to fit a seat about the thoroughfare and is carried loosely upon a pin or support D, with 70 a spring E between the support and plate acting against the suction and tending to close the valve upon its seat. In the construction shown the check-valve is applied to a thermostatic valve device of the character shown in Letters Patent No. 642,533, January 30, 1900, in which the thoroughfare is formed in a seat-piece F and consists of transverse passage-ways f, meeting in a central opening g in the top, with vertical passage-ways c extending through the piece, but not communicating with the passage-ways f and opening at the top on a lower level than the central opening g. When the valve is 75 open, the air and water of condensation pass 80 through the passage-ways f g c, and when the valve-piece B is expanded by steam it closes the passage-way g and shuts the valve. Such a valve device and its operation are fully described in the Patent No. 642,533 and also in 85 Letters Patent No. 600,653, March 15, 1898.

The check-valve C is located under the base of the seat-piece F, over the passage-ways c, and is loosely supported by a screw D, with the spring E between the screw-head and the 90 check-valve C.

Normally the suction or lower pressure upon the outlet side of the valve will hold

the check-valve C off of its seat and leave the thoroughfare *c* open, to be controlled in the usual manner by the main valve-piece B. If, however, for any cause—for example, sudden 5 or excessive condensation in a radiator or drying-cylinder connected with the valve—a greater suction should be temporarily produced on the inlet side of the valve than on the outlet side, the check-valve C will instantaneously close upon the seat and prevent the water of condensation, air, or vapor in the return being drawn back through the valve into the radiator or cylinder. The instant the abnormal condensation or partial vacuum 10 on the inlet side is reduced and normal conditions are restored the check will be automatically opened and the discharge of the air and water permitted.

To keep the spring E free from oil and dirt, 15 the lower edge of the check C may be provided with a flange *m*, having an inclined inner edge, which will tend to direct such water as may collect upon the check-valve outward away from the screw D and spring E.

The details of construction that have been 25 shown may be varied without departing from my invention.

What I claim as new, and desire to secure by Letters Patent, is as follows:

In a valve device for a steam-heating system in which a suction or lower pressure is produced in the return from the outlet of such valve device, the combination of a valve-body having an inlet and an outlet and a thoroughfare for the passage of water of condensation, an automatically-controlled valve-piece to control said thoroughfare, and an auxiliary check-valve also controlling said thoroughfare and arranged so as to be kept normally open by the suction or lower pressure in the outlet of the valve-body. 30 35 40

In testimony of which invention I have hereunto set my hand.

JOHN A. SERRELL.
